UNITED STATES PATENT OFFICE.

HENRY A. SMART AND WILLIAM H. H. COCKE, JR., OF DANVILLE, VIRGINIA.

FEEDER FOR TENTERING MACHINES.

Application filed April 13, 1922. Serial No. 552,437.

To all whom it may concern:

Be it known that we, HENRY A. SMART and WILLIAM H. H. COCKE, Jr., citizens of the United States, residing at Danville, in the county of Pittsylvania and State of Virginia, have invented certain new and useful Improvements in Feeders for Tentering Machines, of which the following is a specification.

10 This invention has reference to feeders for tentering machines, and its object is to provide simple means whereby various adjustments may be effected to accommodate strips of cloth of different widths and the cloth may be put under different degrees of tension with provision made for releasing the tension at suitable intervals.

20 The tension of the rollers upon the cloth is due to the action of springs which cause the engagement of the rollers with and the release of the cloth from such tension alternately thus stretching the cloth and then releasing it, so that the cloth is stretched and then released solely by the action 25 of the springs and without the necessity for utilizing air pressure as has heretofore been done, the operation proving notably successful in practice as compared with the mode of procedure as heretofore practiced.

30 By the present invention, the cloth is put under tension by the use of springs, and air pressure, such as heretofore used, is avoided, for the maintenance of such air pressure involves complications which are entirely 35 eliminated by the present invention.

The invention will be best understood from a consideration of the following detailed description taken in connection with the accompanying drawings forming part 40 of this specification, with the understanding however that the invention is not confined to any strict conformity with the showing of the drawings, but may be changed and modified so long as such changes and modifications mark no material departure from the salient features of the invention as expressed in the appended claims.

Referring to the drawings:—

Figure 1 is an elevation, partly in section, 50 of a tentering machine constructed in accordance with the invention.

Fig. 2 is a view partly in section on the line 2—2 of Fig. 1.

55 Fig. 3 is a section at right angles to the showing of Fig. 2.

Fig. 4 is a view of the structure for ac-

commodating the machine to cloth of various widths.

Fig. 5 is a plan view of a detail of the structure.

Fig. 6 is a section of the main cloth roller and its support forming part of the machine.

Fig. 7 is a view of a rocking support entering into the machine.

Fig. 8 is a longitudinal section of one of the cloth stretching rollers.

Fig. 9 is a perspective view of a detail of the machine structure.

Referring to the drawings, wherein similar characters of reference designate corresponding parts throughout the several views thereof, the preferred embodiment of the machine as shown therein comprises a pair of base members 1, which may be secured to the floor of a factory or the like in any suitable manner, as by means of the bolts 1'. Rising from these base members 1 are a pair of rod sections 2 fitting into sleeves 2', which have engaged in their upper ends the depending rod sections 2" of the frame or superstructure of the machine. These upper rod sections 2" are adjustably secured in the sleeves 2' by means of set screws 3, which construction and arrangement of parts constitute supporting standards or posts for the frame or superstructure, as aforesaid. Extending between the forward ends of a pair of horizontally disposed bars 4, secured in position at the lower ends of the standards or posts 2, the latter to be hereinafter designated in their entirety by the numeral 2, is a roller 4' about which is directed a length of cloth 5 being treated, and which cloth is assumed to be travelling in the direction of the arrows 6 from a source of supply (not shown). The cloth 5 passes from the roller 4' in an upward direction to one side of the lower guide members 7, thence through a set of stretching rollers 8 and 8' to a second or upper guide member 7', and over a direction changing roller 9 to a feed mechanism (not shown) by means of which the cloth is drawn through the pressure or stretching rollers 8 and 8'.

The guide members 7 and 7' are made fast to a block 10 on each side of the machine, and are secured in desired projecting relation therefrom by means of bolts 11 passing therethrough substantially as shown. These guide members 7 and 7' are preferably made from porcelain, whereby the frictional

effects of the same on the cloth is sufficient for the intended purposes thereof, such as will be hereinafter more fully explained.

Each block 10 terminates in a T-head 12 having arcuate slots 13 on opposite sides of the block 10, said slots 13 being traversed by bolts 14 fastening the head 12 to another block 15. There are two blocks 15 on opposite sides of the machine, and these blocks 15 slide on guide rods 16 made fast to supporting blocks 17 carried by the standards or posts 2 at the upper end thereof. Fast to the rods 16 is a centrally located plate 18 incapable of sliding movement on the rods 16. The plate 18 has one end provided with a series of ratchet teeth 19, and pivoted to the plate 18 is a lever 20 connected on opposite sides of a pivot point 21 to the blocks 15 by links 22, and the lever 20 is provided with a pawl 23 serving to lock or release the lever 20 at the will of an operator, whereby the two blocks 15 may be moved simultaneously in opposite directions to adjust the blocks 15 along the rods 16 as may be desired, and to correspondingly actuate the two plates 10 for the adjustment of the oppositely disposed pairs of movable and stationary pressure rollers to and from each other correspondingly for use on lengths of cloth of varying widths.

The movable pressure rollers 8 and the stationary rollers 8' cooperative therewith are arranged in pairs and in oppositely inclined relation inwardly of the blocks 10, and the stationary rollers 8' are preferably made from porcelain. The movable pressure rollers 8 are shown more or less in detail, in Fig. 8, and each are journaled at their opposite ends within a yoke portion 24 having spread leg portions 25 traversed and held together by spacing sleeves 26 and a bolt 26'. Each of the rollers 8 comprises a roller body 27 of a suitable material, recessed as at 27' at its opposite ends, to receive therein bearing balls 28 between the inner ends of which and the inner walls of the recesses 27' are confined ball bearings 29. The bearing balls 28, together with the roller bodies 27, are carried on bolt-like spindles or shafts 30 passing through the opposite legs of the yoke supports 24. Exterior to the roller bodies 27 are rubber sleeves 31 giving a friction grip to the rollers for stretching action on the cloth 5 during its passage between the same and the stationary rollers 8'.

The yoke supports 24, for the movable pressure or stretching rollers 8, are each provided with a bearing surface 34 against which bears a pusher rod 35 carried and movable in a support 36. The two supports 36 are in the form of casings carried by another casing 37 the casing 36 being made fast to the members 10 by straps 41^a. Within the casting 37 there is journaled a crank

shaft 38 connected to the pusher rod 35 by a pitman 39. Surrounding each of the rods 35 is a spring 40, so that on rotating the crank shafts 38, the rods 35 will be reciprocated and the springs 40 will react upon the rollers 8 to cause the same to approach toward or recede from the stationary rollers 8'. This is accomplished by means of levers 41 being contacted by the opposite edges of the cloth during its passage between the stretching rollers 8 and 8', which levers will act to rotate the crank shafts 38 to cause the rods 35 to move the rollers 8 toward or from the rollers 8'. The casing structures 36 being secured by means of the strap bolts 41^a extending through the blocks 10 participate in the adjustment thereof. The pair of rollers 8' are provided with projections 42 to engage metal bands 43 encircling the other or companion rollers 8, thereby momentarily separating the rollers from direct engagement with the cloth band 5 during each revolution of the same and relieving the stretching tension between the rollers and the material 5 being stretched.

When the machine is set for operation upon the cloth material 5, the guides 7 and 7' and the rollers 8 and 8' are placed at an angle to the travel of the cloth material as indicated in Figs. 1 and 3. By properly adjusting the rollers 8 and 8', the cloth is given a sidewise strain or pull conductive of putting the cloth under the desired tension and smoothing and stretching the same in both transverse and longitudinal directions thereof. When adjusting the machine for service, the cloth material 5 is brought from a suitable source of supply not shown, and passed around the roller 4', and thence upwardly, as shown at Fig. 3, past the lower guides 7 and between the rollers 8 and 8', and then past the upper guide 7' and over the roller 9, thus putting the cloth material under strain, and causing the same to be put under sidewise tension. Periodically, the cloth band 5 is released from the stretching pressure of the rollers 8, the springs 40 yielding to the pressure exerted by the engagement of the pins 42 with the metal bands 43 on the rollers 8, whereby the cloth is temporarily released from the tensioning or stretching action of the rollers thereon. In this manner, the cloth material 5 is stretched by the continued action of the machine, and through its entire length. Beside the manner of release of the rollers 8 and 8' from contact one with the other, as in the engagement of the pins 42 with the metal bands 43, this release is also accomplished by the manipulation of the levers 41 and the opposite side edges of the cloth, whereby when the cloth is stretched to too great a degree, its contact with these levers will result in the operation

of the crank shaft to relieve the tension of the springs 40 on the push rods 35, as has been hereinbefore indicated. Provision is made in the machine for adjusting the pressure 65
rollers and the other rollers or guides associated therewith to vary the stretching tension placed upon the cloth by adjusting the blocks 15, and by means of the lever 20 adapting the machine to various widths of 10 cloth.

From the foregoing, it will be readily apparent that, while a preferred embodiment 15 of the machine has been described and illustrated herein in specific terms and details 15 of construction, arrangement and operation, various changes and modifications of the same may be resorted to without departing from the spirit of the invention, or the scope 20 of the claims appended hereto.

20 What is claimed is:—

1. In an apparatus of the class described, a frame including spaced vertical members, a support swingingly mounted on each of said vertical members, means for rotatively 25 adjusting said supports on said vertical members, a stationary roller carried by each of said supports, and a movable roller yieldably engaged with each of said supports, and between which and the stationary rollers a web of cloth is adapted to be drawn.

2. In an apparatus of the class described, a frame including spaced vertical members, a support swingingly mounted on each of said vertical members, and provided with segmental slots, a clamping device extending through the slots and operating to lock the supports in adjusted position relative to the vertical member, a stationary roller carried by each of said supports, and a movable roller yieldably engaged with each of said supports and between which and the stationary rollers a web of cloth is adapted to be drawn.

3. In an apparatus of the class described, a frame including spaced vertical members, a support swingingly mounted on each of said vertical members, means for rotatively adjusting said supports on said vertical members, a stationary roller carried by each of said supports, a movable roller yieldably engaged with each of said supports and between which and the stationary rollers a web of cloth is adapted to be drawn, and guide rollers carried by the swinging supports above and below the stationary and yieldable rollers.

4. In an apparatus of the class described, a frame including spaced vertical members, a support swingingly mounted on each of said vertical members, means for rotatively adjusting said supports on said vertical members, a stationary roller carried by each of said supports and provided with projecting studs, a movable roller yieldably en-

gaged with each of said supports and between which and the stationary rollers a web of cloth is adapted to be drawn, said yieldable roller being moved away from the stationary roller and the web of cloth engaged thereby.

5. In an apparatus of the class described, a frame including spaced vertical members, a support swingingly mounted on each of said vertical members, means for rotatively adjusting said supports on said vertical 75 members, a stationary roller carried by each of said supports, a movable roller coacting with each of said stationary rollers, a casing coupled to each of said swinging supports, a plunger spring supported in each 80 of said casings and operative to yieldably hold the movable rollers, a gage rod swingingly supported in each of said casings and influenced by the spring supported plungers and extending into the path of the web of 85 cloth, and a movable roller yieldably engaged with each of said supports and between which and the stationary rollers a web of cloth is adapted to be drawn.

6. In an apparatus of the class described, a frame including spaced vertical members, a support swingingly mounted on each of said vertical members, means for rotatively adjusting said supports on said vertical members, a stationary roller carried by each of said supports, a yoke device swingingly coupled to each of said supports, a roller pivoted in each of said yoke devices and between which and the stationary rollers a web of cloth is adapted to be drawn, a casing coupled to each of said swinging supports, a plunger spring supported in each of said casings and bearing respectively against said yoke devices and yieldably holding the movable rollers toward the stationary rollers, and a gage rod swingingly supported in each of said casings and influenced by the spring supported plungers and extending into the path of the web of 100 cloth.

7. In an apparatus of the class described, supporting members in spaced relation, a stationary roller carried by each of said supporting members, a movable roller carried by each of said supporting members and between which and the stationary rollers a web of cloth is adapted to pass, means for yieldably supporting the movable member, and studs projecting from the stationary roller and periodically engaging the movable roller and moving it away from the stationary roller and the web of cloth engaged thereby.

In testimony whereof, we affix our signatures hereto.

HENRY A. SMART.
WILLIAM H. H. COCKE, JR.
